PAINTER'S PAIL

Ludger A. Ouellette, West Hartford, Conn., assignor of one-half to Roger B. Rudder, Avon, Conn.

Application September 24, 1957, Serial No. 685,875

1 Claim. (Cl. 15—121.3)

This invention relates to a painter's pail and more particularly to a pail that is primarily intended for use with paint rollers.

An object of my invention is to provide a pail which is adapted to contain a substantial amount of paint, in which the roller is dipped, and which pail is provided with means for conveniently and quickly extracting the superfluous paint from the roller.

A further object of this invention is to provide a pail which will greatly facilitate the use of a paint roller.

Further objects and advantages of the invention will be more clearly understood from the following description and from the accompanying drawing in which:

Fig. 1 is a plan view of a painter's pail embodying the present invention.

Fig. 2 is a sectional side view thereof.

Fig. 3 is a rear view of the rolling plate used in connection with this invention.

As shown in the drawing, my improved painter's pail includes a container 5 having a bottom 6 with side walls 7—7 and upwardly extending end walls 8—8, each of which is inclined outwardly at an angle of approximately seventy degrees since it has been found that this angle is most appropriate for the best results.

The said pail is provided with brackets 9—9 upon which there is pivotally mounted a handle bail 10 having a central notch 11 formed therein to prevent slipping of the handle and unbalancing of the pail when it is hung on a hook or the like.

My invention is particularly directed to the provision of an improved roller loading device for facilitating the use of a paint roller. The said device includes a rolling plate 12 which is preferably corrugated horizontally and mounted upon a pair of vertical supporting bars 13—13 having hook portions 14—14 by means of which the said plate is hung over the edge of one of the end walls 8. The said supporting bars are also provided with foot portions 15—15 which space them from the end wall so as to provide a space between the rolling plate and said end wall, as clearly illustrated in Fig. 2.

2

The said rolling plate 12 has a suitable number of perforations 16 through the upper portion thereof for the passage of paint which is extracted from the roller. A stop bar 21 extends across said plate and is adapted to engage the roller and prevent it from being carried off the said rolling plate.

In order to support the conventional roller, indicated in dotted lines at 17, within said pail, I provide a supporting bracket 18 which preferably includes a pair of roller supporting portions 19—19 having hook portions 20—20 which are adapted to fit over the edge of the opposite end wall 8 to mount said bracket thereon.

In the use of my improved pail, paint is placed therein, preferably up to the level indicated at 22. The roller 17 is then held by its handle, dipped into said paint and then rolled upwardly against the rolling plate 12. This extracts the surplus paint from the surface of the roller and said surplus paint then passes through the perforations 16 and drains downwardly, between the rolling plate and the respective end wall 8, back into the paint at the bottom of the pail.

It will be noted that when the roller 17 is rolled up and down against the plate 12, the bar 21 will prevent the roller from rolling off said plate and thereby facilitates the operation of extracting the surplus paint from the roller.

When the roller is not being used, it is merely placed in the brackets 19 and the handle of said roller will rest upon the bar 21 as clearly shown in Fig. 2.

30 I claim:

In a painter's pail having a bottom, side walls, end walls diverging upwardly from said bottom, a corrugated surface on one of said end walls and a stop bar disposed transversely upon the upper portion of said corrugated surface and extending inwardly therefrom; the combination of a bracket mounted upon the opposite end wall of said pail and including hook means extending over the edge of said opposite end wall for supporting the bracket thereon, and a pair of spaced hooks disposed inwardly of said pail and adapted for receiving and supporting a paint roller with the handle thereof resting upon said stop bar.
